UNITED STATES PATENT OFFICE.

CHRISTIAN BECKER, OF BELOIT, WISCONSIN, ASSIGNOR TO THE MATTISON MACHINE COMPANY, OF SAME PLACE.

ABRADING OR POLISHING MACHINE.

SPECIFICATION forming part of Letters Patent No. 629,885, dated August 1, 1899.

Application filed January 9, 1899. Serial No. 701,542. (No model.)

To all whom it may concern:

Be it known that I, CHRISTIAN BECKER, a citizen of the United States, residing at Beloit, in the county of Rock and State of Wisconsin, have invented a new and useful Abrading or Polishing Machine, of which the following is a specification in its best form now known to me, reference being had to the accompanying drawings.

10 My invention relates to machines for polishing and finishing wood, iron, or other materials.

It consists particularly in a machine in which a continuously-moving, flexible, and approximately flat abrading or polishing pad is presented to the work. Many machines having one or more cylindrical abrading or polishing rolls have been heretofore used, and I do not claim these.

20 It also consists in the form and construction of the pad and the method of securing the abrading or polishing material thereto.

It also relates to the means of driving and controlling the pad and to details of construction hereinafter more fully described and claimed.

25 For convenience the machine is shown and will be described as a wood-polishing machine; but by substituting emery-paper, or other abrading material for the sandpaper it may be used on iron and many other materials.

In the drawings, Figure 1 is an end, Fig. 2 a side sectional view, Fig. 3 a plan, and Fig. 35 4 an end sectional view, of my improved machine. Fig. 5 is a detail of the belt. Fig. 6 is a detail view of the feed-table between the rollers and the roller-bearings.

40 Mounted in suitable end frames 11 is a main shaft 12, having rigidly secured to it a flanged pulley 13. On the end of each end frame 11 are bolts 14, passing through slotted holes 15 in a yoke 16. The yoke is adapted to slide up and down on the frame between 45 guiding-lugs 17. In the center of the end frame is another lug 18, in which a screw 19 is adapted to turn up and down. This screw also passes through lugs 20 on yoke 16 and has rigidly secured to it between them the nut 21, so that turning this nut will turn the screw and move the whole yoke up and down.

Passing through the side lugs 22 on the yoke 16 are set-screws 23, which screw into and rigidly hold bearings 24 for shaft 12. It will be seen that by loosening one screw 23 and 55 tightening the other the shaft may be adjusted sidewise, and that by loosening screws 14 and turning screw 19 by nut 21 the yoke 16, and consequently shaft 12, may be raised or lowered, and that by then tightening 60 screws 14 the whole may be securely locked in position. To accommodate this and other adjustments, the end frames have in them the large rectangular openings 27.

The end frames are rigidly attached to 65 together by suitable connecting-rods and braces 25 and the top plate or working table 26. To the under side of this table 26 and in line with the openings 27 of the end frames are secured by bolts 28 the castings 29. In each 70 of these castings is the rectangular slot 30.

The rollers 31 are journaled on castings 32, (on dotted lines, Fig. 3,) bolted to the feed-table 33, which is between the rollers. This feed-table between the rollers is of a semi-75 triangular cross-section, as shown in Fig. 4, and where it extends beyond the rollers is a rectangular bar 34, adapted to fit in and slide endwise in the slot 30 in casting 29. The rectangular bar has bolted to it by bolts 35 80 the castings 32, which form bearings for the rollers, as above described.

At one end of the machine the bar 34 of the feed-table is rigidly connected by rod 36 to the shaft 12, so that the flanged drum 13 and 85 the rollers 31 may be, if desired, reciprocated endwise. The extent of such motion is limited by a screw or pin 37, rigidly secured to bar 30 and adapted to slide in a slotted hole cut in the side of casting 29. The screws 28 in 90 casting 29 pass through slots 38 in table 26, so that by moving the screws the castings, and consequently the rollers, are capable of a side-wise adjustment.

Passing over the flanged pulley 13 and the 95 rollers 31 is a belt 39, of leather, rubber, canvas, or other suitable material. The leather or rubber flanges 40 are riveted to this belt at its outer edges. The width of the belt, or, rather, the width between these flanges 40, is the width of the working surface of the machine. Stretched around this leather, can-

vas, or rubber belt is placed another continuous belt of sandpaper 41; but this sandpaper is not secured to the leather by pegs, nails, glue, or other mechanical means. The leather or rubber belt may be corrugated, as shown in Fig. 5, so as to allow air-spaces or pads between it and the sandpaper belt. I also find that the operation of the machine is slightly improved by inserting a belt of canvas or other woven material between the sandpaper and leather belts. To put on the sandpaper belt, the leather belt is loosened by raising the shaft 12 and pulley 13 in the manner described. I then take a piece of sandpaper of sufficient length and temporarily secure one end to the leather belt by means of a strip of spring-steel inserted under the flanges 40. I then by hand turn the leather belt a complete revolution, remove the steel spring, bring the two ends of the sandpaper together, and glue or cement them. When the joint is dry, I lower the shaft 12 in the manner described to its original position, thus tightening both belts and by friction securing the sandpaper belt to the leather one.

One great difficulty in making a satisfactory abrading-belt is that the strain due to the difference in rate of travel of the surface of the leather belt and the sandpaper belt in passing over small rollers is so great that sandpaper which is mechanically fastened to the belt will soon become very rough and be torn to bits in a very short time, even when it is doing no work. The reason is seen in the demonstrated fact that the sandpaper belt on my machine when tightly stretched on the leather belt gains half an inch, more or less, in travel in each complete trip of the leather belt, but it does this without in any way injuring the sandpaper, which may be used until it is worn out in the ordinary course of work. Another difficulty is that any roughness in a straight-running belt will make straight scratches in the work. By fastening the sandpaper belt in the manner described and by giving the belt a reciprocating motion I have produced a machine which does away with both of these difficulties.

The table 26 is cut away, as shown in Figs. 3 and 4, to allow the sandpaper surface to come up on a level with it and to allow for the passage of the flanges 40 of the main belt.

In the operation of my machine I first raise the shaft 12 and apply the sandpaper belt over the leather belt in the manner described. I then lower the shaft and tighten both belts. I then apply power to a pulley (not shown) on shaft 12 and rapidly rotate the shaft and pulley 13, thereby causing the sandpaper belt to travel continuously over the rollers 31 on a level with the table 26. Wood or other materials which it is desired to polish are now passed along the top of the table and are polished and finished by the broad rapidly-moving flat but flexible pad of sandpaper. Whenever the sandpaper wears out, all that is necessary is to cut it off by running a knife once

the length of the pad and put on a new belt in the original way. As heretofore pointed out, all that is here said of the sandpaper belt would apply with equal force to an emery-paper, emery-cloth, or other abrading or polishing material.

If it is desired to give the sand-pad a reciprocating motion, this may be done by applying any of the well-known means of producing such motion to the shaft 12. The rollers being connected to the shaft by rod 36, as heretofore described, the large pulley, small rollers, and belt will all move together.

Having thus described my invention, what I claim as new, and desire to secure by Letters Patent, is—

1. In an abrading or polishing machine, the combination of a working table and a belt of abrading or polishing material stretched over two or more rollers adapted to be reciprocated endwise so journaled below said table that when said belt is passed over said rollers it will travel flatwise for a considerable distance at substantially the level of the top of said table.

2. In an abrading or polishing machine, the combination of a working table, a belt of abrading or polishing material stretched over two or more rollers adapted to be reciprocated endwise so journaled below said table that when said belt is passed over said rollers it will travel flatwise for a considerable distance at substantially the level of the top of said table, and means for so driving said belt over said rollers.

3. In an abrading or polishing machine, the combination of a working table, two or more rollers adapted to be reciprocated endwise journaled below said table with their upper surfaces substantially on a level with the top of said table, a pulley below said rollers, a belt of abrading or polishing material stretched over said rollers and pulley, and means for applying power to said pulley whereby said belt is made to travel flatwise over said rollers for a considerable distance at substantially the level of the top of said table.

4. In an abrading or polishing machine, the combination of a working table and a continuous working belt adapted to travel for a considerable distance flatwise along said table at substantially its upper surface, said working belt consisting of an inner permanent flanged belt having corrugations on its surface and an outer temporary belt, of abrading or polishing material, stretched over the corrugated surfaces of the first belt, but not otherwise secured thereto.

5. In an abrading or polishing machine, the combination of a working table, two or more rollers journaled below said table with their upper surfaces substantially on a level with the top of said table, a pulley below said rollers, a permanent flexible belt stretched over said rollers and pulley, another belt of abrading or polishing material stretched over said first belt, but not otherwise secured thereto,

and means for applying power to said pulley whereby the abrading or polishing surface of said second belt is made to travel flatwise over said rollers at substantially the level of the top of said table.

5. In a machine of the class described, two or more small rollers adjacent to the feed-table, a pulley below said rollers, a belt covered with abrading or polishing material over said rollers and pulley, and a rod rigidly connecting the bearings of said rollers with the shaft of said pulley whereby if said shaft is given an endwise reciprocating motion said rollers and belt will be given the same motion.

15. 7. In a machine of the class described, two or more small rollers adjacent to the feed-table, a pulley below said rollers, a belt over said rollers and pulley, and means for supporting the shaft of said pulley so that it may be adjusted up or down or sidewise whereby said belt may be adjusted upon said pulley and rollers, substantially as described.

8. In an abrading or polishing machine, the combination of a working table, and a continuous working belt adapted to travel for a considerable distance flatwise along said table at substantially its upper surface, said working belt consisting of an inner permanent canvas belt and an outer temporary belt of abrading or polishing material stretched over said canvas belt, but not otherwise secured thereto.

9. In an abrading or polishing machine, the combination of a working table, and a continuous working belt adapted to travel at substantially its upper surface, said working belt consisting of an inner permanent flanged belt and an outer temporary belt of abrading or polishing material, stretched over said first belt between its flanges, but not otherwise secured thereto.

40. 10. In an abrading or polishing machine, the combination of a central bar or feed-table,

a pair of rollers journaled in bearings rigidly secured to said feed-table, the top of said feed-table being substantially on a level with the top of said rollers, substantially as described.

11. In an abrading or polishing machine, a central bar or feed-table, a pair of rollers so journaled in bearings rigidly secured to said feed-table that the tops of said rollers are approximately on a level with the top of said feed-table, and a belt of polishing material stretched over said rollers and feed-table, in combination with a permanent working table in which the central bar or feed-table is so mounted that said polishing-belt will travel flatwise on a level with the top of the working table.

12. In an abrading or polishing machine, a central bar or feed-table, a pair of rollers so journaled in bearings rigidly secured to said feed-table that the tops of said rollers are approximately on a level with the top of said feed-table, and a belt of polishing material stretched over said rollers and feed-table, in combination with a permanent working table in which the central bar or feed-table is so mounted that said polishing-belt will travel flatwise on a level with the top of the working table and may be simultaneously reciprocated sidewise.

13. In a machine of the class described, a main shaft, a pulley on said shaft, two rollers journaled in bearings rigidly connected to said shaft, and a belt of abrading material stretched over said rollers and pulley, whereby if the shaft be given a reciprocating motion said pulley, roller and belt will be given the same motion.
